(57) **CLAIM**

The ornamental design for a fishing line threading device, as shown and described.

DESCRIPTION

FIG. 1 is a front perspective view of a fishing line threading device, shown with a gripping head extended from a sleeve of the fishing line threading device with the gripping head in an expanded configuration;

FIG. 2 is a left side elevation view thereof;

FIG. 3 is a front elevation view thereof;

FIG. 4 is a top plan view thereof;

FIG. 5 is a right side elevation view thereof;

FIG. 6 is a rear elevation view thereof;

FIG. 7 is a top plan view thereof, shown with the gripping head withdrawn into the sleeve, which is shown in cross section taken along the lines 7-7 of FIG. 1, with the gripping head in a contracted configuration within the sleeve; and, FIG. 8 is an exploded perspective view thereof.

The broken lines depict environmental structure and are for illustrative purposes only and form no part of the claimed design.
